SANDING DEVICE

Filed Feb. 25, 1950

INVENTOR:

William Naken,

BY Dawson, Osce, Broth and Spangenberg,
ATTORNEYS.

This is a continuation-in-part of my application, Serial No. 146,177, filed February 25, 1950, now pending.

This application is for a sanding device which is an improvement of the device shown in my original application. The improvement is in the manner of holding an abrasive sheet on the blade.

This invention relates to sanding devices and more particularly to devices for holding abrasive sheets such as sheets of sandpaper or the like for performing sanding or polishing operations.

For sanding operations it is essential that the abrasive sheet be held firmly against slipping or wrinkling. It is also essential that the user be able to hold and manipulate the abrasive firmly and comfortably.

It is one of the objects of the present invention to provide a sanding device which will hold an abrasive sheet firmly and which is easy and convenient to handle.

Another object is to provide a sanding device including a blade to hold an abrasive sheet and a handle lying at an obtuse angle to the blade.

Still another object is to provide a sanding device in which an abrasive sheet is held on the blade by a fastening plate secured to the blade.

A further object is to provide an extremely simple and efficient fastening means to secure the fastening plate to the blade.

The above and other objects and advantages of the invention will be more readily apparent when read in connection with the accompanying drawings, in which—

Figure 1 is a perspective view of a sanding device embodying the invention;

Figure 2 is a view similar to Figure 1 showing the parts disassembled;

Figure 3 is a longitudinal central section through the device of Figure 1;

Figure 4 is a transverse section on the line 4—4 of Figure 3; and

Figure 5 is a view similar to Figure 4 showing an alternative construction.

The sanding device of the present invention consists essentially of a flat, relatively thin blade indicated generally at 10 and a handle 11 rigidly secured to the blade and extending at an obtuse angle therefrom at one end. The blade is preferably made of sheetmetal and may be attached to a separate handle 11, as illustrated, or may have the handle formed integrally therewith, if desired. The blade in the form shown in Figures 1 to 4 includes a flat central portion and edge portions 12 which are turned up slightly at an obtuse angle to avoid sharp corners on the working surface of the blade. In its central part the blade carries an upstanding ear 13 which may be welded or riveted to the metal blade and which is formed with an opening 14 therethrough.

The blade is adapted to receive an abrasive sheet 15 such as sandpaper, emery paper, or the like and which is rectangular and of slightly

SANDING DEVICE

William Naken, Chicago, Ill.

Application February 25, 1950, Serial No. 146,177

4 Claims. (Cl. 51—187)

1.

This invention relates to sanding devices and more particularly to devices for holding abrasive sheets such as sheets of sandpaper or the like for performing sanding or polishing operations.

For sanding operations it is essential that the abrasive sheet be held firmly against slipping or wrinkling. It is also essential that the user be able to hold and manipulate the abrasive firmly and comfortably.

It is one of the objects of the present invention to provide a sanding device which will hold an abrasive sheet firmly and which is easy and convenient to handle.

Another object is to provide a sanding device including a blade to hold an abrasive sheet and a handle lying at an obtuse angle to the blade.

Still another object is to provide a sanding device in which an abrasive sheet is held on the blade by a fastening plate secured to the blade.

A further object is to provide an extremely simple and efficient fastening means to secure the fastening plate to the blade.

The above and other objects and advantages of the invention will be more readily apparent when read in connection with the accompanying drawings, in which—

Figure 1 is a perspective view of a sanding device embodying the invention;

Figure 2 is a view similar to Figure 1 showing the parts disassembled;

Figure 3 is a longitudinal central section through the device of Figure 1;

Figure 4 is a transverse section on the line 4—4 of Figure 3; and

Figure 5 is a view similar to Figure 4 showing an alternative construction.

The sanding device of the present invention consists essentially of a flat, relatively thin blade indicated generally at 10 and a handle 11 rigidly secured to the blade and extending at an obtuse angle therefrom at one end. The blade is preferably made of sheetmetal and may be attached to a separate handle 11, as illustrated, or may have the handle formed integrally therewith, if desired. The blade in the form shown in Figures 1 to 4 includes a flat central portion and edge portions 12 which are turned up slightly at an obtuse angle to avoid sharp corners on the working surface of the blade. In its central part the blade carries an upstanding ear 13 which may be welded or riveted to the metal blade and which is formed with an opening 14 therethrough.

The blade is adapted to receive an abrasive sheet 15 such as sandpaper, emery paper, or the like and which is rectangular and of slightly

2.

greater width than the blade itself. Preferably, the abrasive sheets employed are substantially the full length of the blade but wider than the blade, as indicated. The abrasive sheets are adapted to overlie the bottom surface of the blade with their edge portions folded about the edges of the blade and extending partially over the upper surface of the blade. Preferably, as shown in Figure 4, the abrasive sheet is wide enough to extend over the upwardly bent edges 12 of the blade to the flat top surface thereof.

To hold the abrasive sheet in place, a fastening plate 16 is provided which is narrower than the blade and slightly shorter. Preferably, the fastening plate has a flat central portion with downwardly turned edges 17 to engage the abrasive sheet substantially at the angle of the bent edge portions 12 of the blade. To hold the fastening plate, it is provided with a U-shaped opening 18 leaving a tongue 19 extending longitudinally of the plate and of a size to be received in the opening 14 of the ear 13.

To use the device an abrasive sheet may be folded around the blade, as illustrated, and the fastening plate 16 may be placed over the blade and the sheet and slid longitudinally to move the finger 19 into the opening 14. This will securely hold the fastening plate over the blade, pressing the edges of the blade against the abrasive sheet to hold it tightly against shifting. The blade itself and the finger 19 will provide sufficient resilience to insure tight gripping of the abrasive sheet. With the sheet secured in place, the user may grip the handle 11 and may manipulate the device much in the manner of a file. The upwardly turned edge 12 will insure against sharp corners on the working surface which might bite into the work so that the device can be used easily and effectively. Worn abrasive sheets can be replaced very easily and quickly and will be securely held against the blade when in use.

In the modification illustrated in Figure 5, the blade 10' is rolled upward at its edges, as indicated at 12' to provide rounded bead like edges. The fastening plate 16' is narrower than the space between the rolled edges 12' so that it will grip the abrasive sheet 15' in the manner illustrated. Otherwise this construction is the same as that of Figures 1 to 4 and functions in exactly the same manner.

While two embodiments of the invention have been shown and described in detail herein, it will be understood that they are illustrative only and are not to be taken as a definition of the scope

of the invention, reference being had for this purpose to the appended claims.

What is claimed is:

1. A sanding device comprising a handle and a blade rigidly connected end to end and lying at an obtuse angle to each other, the blade being adapted to receive an abrasive sheet overlying the blade bottom with its edge portions folded over the edges of the blade and extending partially over the top of the blade, a fastening ear extending upward from the top of the blade, a fastening plate to overlie the top of the blade and grip the folded edges of the abrasive sheet, and an integral finger on the plate to engage the fastening ear upon sliding the plate relative to the blade to secure the plate to the blade.

2. A sanding device comprising a handle and a blade rigidly connected end to end and lying at an obtuse angle to each other, the blade being adapted to receive an abrasive sheet overlying the blade bottom with its edge portions folded over the edges of the blade and extending partially over the top of the blade, a fastening ear extending upward from the top of the blade and having an opening therein, a fastening plate to overlie the top of the blade and grip the folded edges of the abrasive sheet, the plate having an opening therein through which the ear may project, and an integral tongue on the plate to fit into the opening in the ear to secure the plate to the blade.

3. A sanding device comprising a handle and a blade rigidly connected end to end and lying at an obtuse angle to each other, the blade being adapted to receive an abrasive sheet overlying the blade bottom with its edge portions folded over the edges of the blade and extending partially over the top of the blade, a fastening ear ex-

tending upward from the top of the blade and having an opening therein, a fastening plate to overlie the top of the blade and grip the folded edges of the abrasive sheet, the plate having a U-shaped opening therein to receive the ear and to define an integral tongue adapted to fit into the opening in the ear to secure the plate to the blade.

4. A sanding device comprising a handle and a relatively thin flat blade lying at an obtuse angle to the handle, the handle being bent upward at its edges and adapted to receive an abrasive sheet overlying its bottom with its edge portions folded over the upwardly bent edges of the blade and extending partially over the top of the blade, a fastening plate to fit over the top of the blade between the upwardly bent edges to grip the folded edges of the abrasive sheet, an upwardly extending ear on the blade having an opening therein, the plate having an opening therein to receive the ear, and an integral tongue on the plate to fit into the opening in the ear to secure the plate to the blade.
